UNITED STATES PATENT OFFICE.

OMER M. GLUNT, OF RUTHERFORD, NEW JERSEY, ASSIGNOR TO WESTERN ELECTRIC COMPANY, INCORPORATED, OF NEW YORK, N. Y., A CORPORATION OF NEW YORK.

ELECTROMAGNET.

1,291,831.

Specification of Letters Patent. Patented Jan. 21, 1919.

Application filed June 22, 1917. Serial No. 176,381.

To all whom it may concern:

Be it known that I, OMER M. GLUNT, a citizen of the United States, residing at Rutherford, in the county of Bergen and 5 State of New Jersey, have invented certain new and useful Improvements in Electromagnets, of which the following is a full, clear, concise, and exact description.

This invention relates to electromagnets 10 and more particularly to an improved method for supporting the armature of an electromagnet.

The object of this invention is to provide a structure efficient in operation, and cheap 15 to manufacture and assemble, and one in which the adjustment of the armature with respect to the pole pieces is easily obtained and remains permanent in service.

To attain this object, in accordance with 20 a feature of the invention, the ends of the cores are recessed to receive steel rings which are snapped into place during assembly and provide shoulder portions against which the yoke and armature bridge are securely held 25 by means of an adjusting screw.

This and other features of the invention may be more clearly understood by reference to the accompanying drawing, in which Figure 1 is a view partially in section of a 30 structure embodying the invention as applied to a telephone ringer; and Fig. 2 is an expanded view showing the various parts of Fig. 1 separated and in position for assembling. For the sake of simplicity, the 35 gongs and upper portion of the ringer are not shown in the drawing since they form no part of the present invention.

The magnet spools 3, 3 each provided with a core 4 of magnetic material are joined 40 by a suitable yoke 5 of a non-magnetic material. This yoke is provided with perforations 6, 6 of suitable dimensions to fit over the cores and is held in place by the steel rings 7, 7 which during assembly are snapped into the grooves 8, 8 provided in the cores. The armature 9 to which is attached the well-known form of clapper rod 10, is pivotally mounted to right-angle extensions of the armature bridge 11 of brass 45 or other non-magnetic material. The ends of the bridge 11 are U-shaped, or, in other words, the ends are bent back toward each other, and are provided with perforations 12, 12 adapted to fit over the ends of the 50 cores. The adjustment of the armature 9

with respect to the ends of the cores 4, 4 is obtained by means of the adjusting screw 13 which extends through the perforation 14 in the armature bridge 11 and the perforation 15 in the armature 9, and engages 60 threads in the embossed hole 16 in the yoke 5. The head of the screw shoulders against the countersunk portion of perforation 14, hence as the screw is turned the yoke 5 and the ends of bridge 11 are drawn against the 65 rings 7, 7, thereby holding the various parts securely in place. Further turning of the screw 13 results in flexing the armature bridge 11 and allowing the armature to approach the ends of the cores, thereby providing a simple means of adjustment. A perforation 17 is provided in the magnet 70 18 to permit the use of a screw driver to easily change the adjustment of the ringer.

In the structure as described, it will be noted that it is not necessary to restrict the cross-section of the core an appreciable amount to afford means for mounting the armature and its support. Practically the entire cross-section of the core is therefore effective, resulting in an efficient magnetic circuit and insuring a higher impedance to a winding of a given number of turns; this high impedance in turn resulting in a lower shunting effect on high frequency voice currents. The manner of flexing the armature bridge in which the ends are bent back at an angle of 180° permits a greater effective length to this part, thereby affording a more sensitive adjustment on account of the 80 greater resiliency of the armature bridge and also lessens the possibility of the metal taking a permanent set. 85

What is claimed is:

1. In an electromagnet, the combination 95 of a pair of cores having grooves therein, an armature bridge engaging said cores, a yoke extending between said cores and non-adjustable means coöperating with said grooves to provide an abutting member 100 whereby said yoke and the ends of said armature bridge are held in a fixed position with respect to said cores.

2. In an electromagnet, the combination 105 of a pair of cores having grooves therein, an armature bridge engaging said cores, a yoke extending between said cores and spring rings coöperating with said grooves to provide an abutting member whereby said yoke and the ends of said armature bridge are 110

held in a fixed position with respect to said cores.

3. In an electromagnet, the combination of a pair of cores having grooves therein, an armature bridge having its opposite ends bent toward each other to engage said cores, and spring rings coöperating with said grooves to position said armature bridge with respect to said cores.

10 4. In an electromagnet, the combination of a pair of cores having grooves therein, a yoke interconnecting said cores, and located on one side of the grooves, an armature bridge located on the other side of said grooves, and means independent of said yoke coöperating with said grooves to hold said yoke and the ends of said armature bridge in a fixed position.

15 5. In an electromagnet, the combination of a pair of cores having grooves therein, a yoke extending between said cores, and lo-

cated on one side of the grooves, an armature bridge engaging said cores, and located on the other side of said cores, means coöperating with said grooves to position said 25 yoke and bridge with respect to said cores, and additional means for holding said yoke and armature bridged in locked engagement with said first means.

6. In an electromagnet, the combination 30 of a pair of cores having grooves therein, a yoke extending between said cores, an armature bridge engaging said cores, an armature pivotally mounted in said bridge, spring rings coöperating with said grooves 35 to provide an abutting member for said bridge and yoke, and means for flexing said bridge to determine the position of said armature relative to said cores.

In witness whereof, I hereunto subscribe 40 my name this 18th day of June, A. D. 1917.

OMER M. GLUNT.
